DESIGN FOR AN ELECTRICAL TEST PLUG

John D. Tuomey, Forest Hills, N. Y., assignor to
Union Aircraft Products Corporation, New
York, N. Y., a corporation of New York

Application July 15, 1944, Serial No. 114,416

Term of patent 14 years

(Cl. D26—1)

To all whom it may concern:

Be it known that I, John D. Tuomey, a citizen
of the United States, residing at Forest Hills, in
the county of Queens and State of New York,
have invented a new, original, and ornamental
Design for an Electrical Test Plug, of which the
following is a specification, reference being had
to the accompanying drawing, forming a part
thereof.

Figure 1 is a side view of an electrical test plug
embodying my new design;

Figure 2 is a top view; and

Figure 3 is a bottom view.

I claim:

The ornamental design for an electrical test
plug, as shown.

JOHN D. TUOMEY.
